UNITED STATES PATENT OFFICE.

NICHOLAS WITSCHI, OF JERSEY CITY, NEW JERSEY, ASSIGNOR TO THE AMERICAN LITHOGRAPHIC COMPANY, OF NEW YORK, N. Y.

DESIGN FOR A LABEL.

SPECIFICATION forming part of Design No. 32,675, dated May 22, 1900.

Application filed March 12, 1900. Serial No. 8,415. Term of patent 7 years.

To all whom it may concern:

Be it known that I, NICHOLAS WITSCHI, a citizen of the United States, residing at No. 100 Palisade avenue, Jersey City, in the county 5 of Hudson and State of New Jersey, have invented and produced a new and original Design for a Label, of which the following is a specification, reference being had to the accompanying drawing, forming a part thereof.

10 My design is intended for use as a label. In the accompanying drawing, the design, as shown, comprises an eight-pointed star whose center contains a circular panel surrounding a medallion having on it a female head with sixteen stars about it. Two five-pointed stars are seen at either side of the medallion and upon the small panel, whose 15 outer edges are ornamented by a series of minute circles intended to represent beadwork.

The triangular rays composing each of the 20 eight points of the star are filled in by a series of narrow panels radiating from the centers of their several bases. Between the eight points of the star are shown small medals with heads and groups thereon, and radiating from the outer edge of the star design are shown a series of lines. The background has line-shading, giving the effect of clouds. 25

I claim—

The design for a label as herein shown and 30 described.

In testimony whereof I, NICHOLAS WITSCHI, affix my signature in presence of two witnesses.

NICHOLAS WITSCHI.

Witnesses:

JACOB MILLER,
OTTO E. KUGLER.
